(57) **CLAIM**

We claim the ornamental design for a media processing device, as shown and described.

DESCRIPTION

FIG. 1 is a front perspective view of an example media processing device;

FIG. 2 is a top view thereof;

FIG. 3 is a front view thereof; and,

FIG. 4 is a rear view thereof.

In FIGS. 1-4, all sides that are not seen are disclaimed. The dot-dot-dash broken lines depict the bounds of the claimed design, while all other broken lines are directed to environment. The broken lines form no part of the claimed design.

The wire frame lines shown throughout indicate surface contour.
